FUEL INJECTION TIMING APPARATUS

Herbert Deutschmann, Stuttgart-Bad Cannstatt, Germany, assignor to Daimler-Benz Aktiengesellschaft, Stuttgart-Untereuterkheim, Germany.

Application April 7, 1958, Serial No. 726,897

Claims priority, application Germany April 17, 1957

13 Claims. (Cl. 123—139)

This invention relates to an apparatus for adjusting the timing of fuel injection for an internal combustion engine and in particular for a reversible engine in which the fuel injection timing is automatically adjusted in response to changes both in engine speed and direction of rotation.

One of the objects of this invention is to provide an improved fuel injection timing device for an internal combustion engine of the above type.

Another object of this invention is to provide an improved hydraulically operated fuel injection control device, more specifically a device of this type using oil from the engine lubricating system for actuation thereof.

Another object of this invention is to provide an improved device of the above-mentioned type which uses oil pressure from the engine lubricating system for at least partially actuating the device.

Still another object of this invention is to provide an improved hydraulic control system for a device of the above-mentioned type, more particularly a hydraulic control system including means responsive to engine speed for controlling the system.

A further object of this invention is to provide a simplified fuel injection control device that is easily adjusted automatically for proper timing of fuel injection for engine rotation in both directions at various speeds.

The invention relates to a device for the adjustment of the beginning of injection for internal combustion engines with fuel injection which are reversible for right-hand or left-hand rotation and especially those used for driving ships and locomotives. The device responds to the rotative engine speed and, by means of flyweights working against the action of springs to actuate a slide valve, controls a hydraulic auxiliary force which acts on a piston in a cylinder. The piston moves a shaft member in an axial direction which effects in the drive of a fuel injection pump an angular adjustment of the pump drive shaft relative to the crankshaft of the internal combustion engine for automatic adjustment of the beginning of injection for various speeds in both directions of engine rotation.

The invention purports to attain an automatic adjustment of the most suitable beginning of injection with simple means and without rebuilding of reversible internal combustion engines, which without reverse gears are of small weight and used for driving of ships. The invention comprises for right-hand rotation as well as left-hand rotation a pair of flyweights, each pair cooperating with a slide valve. Both valves control the flow of oil delivered by a reversible oil pump, in dependence on the rotative engine speed and direction, to actuate a piston in a cylinder. For right-hand engine rotation, the piston is moved in one direction for an axial adjustment and setting of the drive shaft of the injection pump from a later to an earlier beginning of injection, and for left-hand engine rotation the piston is

2

moved in the other direction for axial adjustment and setting from a later to an earlier beginning of injection.

The control arrangement can be made so that the slide valves cooperating with the flyweights are arranged coaxially with each other and enclose a valve-adjusting piston therebetween which, in dependence on the oil pressure acting on the piston in the cylinder and controlled by one slide valve for one direction of engine rotation, brings the other slide valve, which controls the oil pressure in the other direction of rotation, out of contact with the flyweights that cooperate therewith so as to be inoperable thereby.

According to another feature of the invention for operation of the internal combustion engine in one direction, the oil delivered at one pressure by the pump for the movement of the piston in the cylinder in one axial direction may be advantageously controlled by one slide valve, and the other slide valve controls, at the same time, the admission of oil at a smaller pressure into the cylinder for effecting a restoring force which acts against the adjusting force on the piston and vice versa.

In the pressurized oil circuits which effect the adjusting force and the smaller restoring force, the delivery lines, the control openings and the discharge lines may advantageously have functions depending on direction of engine rotation whereby the operation of the system may be readily reversed.

The oil pump which furnishes oil under pressure for adjusting the force on the piston may be connected to the pressurized lubricating oil circuit of the internal combustion engine.

The oil pump suction and discharge chambers, which are alternately interchanged in their functions depending on the direction of engine rotation, may each be provided with an inlet valve and an outlet valve, preferably ball valves not spring loaded, to prevent reverse flow at each valve.

Furthermore, the inlet or supply valves for both pump chambers may be connected to a common supply conduit while the outlet valves of the respective pump chambers may, however, be arranged in independent discharge lines through one of which, depending on the direction of rotation of the oil pump, flows oil for effecting the adjusting force and through the other is delivered oil of the pressure of the lubrication oil system for effecting the restoring force. Advantageously, both pressure oil circuits for the adjusting device may be conducted thereto in an axial direction at opposite sides thereof.

In the preferred embodiment of the invention, the main adjusting piston and the centrifugally actuated control valves therefor are rotatable with the driving shaft of the fuel injection pump and the cylinder which encloses the piston and valve means.

The foregoing and other objects, features and advantages of the present invention will become more obvious from the following description when taken in connection with the accompanying drawing, which shows, for purposes of illustration only, one embodiment in accordance with the present invention, and wherein:

60 Figure 1 is a longitudinal section through a fuel injection timing device with a reversible gear pump connected thereto and shown in a larger scale; and

65 Figure 2 is a partial section of the control device of Figure 1 with some of the control elements in different operating positions.

Inside a housing 1, a hollow shaft 2, which in four-cycle internal combustion engines rotates at half the crankshaft speed, is supported in bearings 3, 4 and is not axially slidable. Between the bearings 3, 4 the hollow shaft 2 forms a cylinder 5 in which is arranged a disk-shaped piston 6 which divides the cylinder into two

chambers 7, 8. The piston 6 is solidly connected with a tubular shaft 9 and both are slidably in the hollow shaft 2.

Inside the tubular shaft 9, axially slidable valves 10, 11 are arranged to enclose between them an axially slid-able valve-adjusting piston 12. The slide valves 10, 11 are provided at their outer circumference with annular grooves 13 and 14, respectively, and have axially di-rected bore holes 15 and 16, respectively. The slide valves 10, 11 are connected with the abutment members 23 and 24, respectively, which are slidably arranged on the hollow shaft 2, by means of bolts 17 and 18 which extend respectively transversely through the slide valves, longitudinal grooves 19 and 20 in the tubular shaft 9, and longitudinal grooves 21 and 22 in the hollow shaft 2. The abutment members 23, 24 support ends of control compression springs 25 and 26, respectively, which in turn are positively supported at their other ends on the hollow shaft 2. When the control is inactive, springs 25 and 26 act through the abutments 23 and 24 to move both valves 10 and 11 against piston 12. In the range of the longitudinal grooves 21 and 22, respectively, bore holes 27 and 28, respectively are provided in the abutment members 23 and 24, respectively. Levers 29 of flyweights 30 abut against the abutment member 23 and are pivotally mounted on one end of the cylinder 5. Levers 31 of flyweights 32 abut against the abutment member 24 and are pivotally mounted on the other end of the cylinder 5.

An oil pump 33, which is preferably arranged inside the housing 1, is a gear pump having gears 34, 35 and suction and discharge chambers 36, 37 which are inter-changeable in operation. A common oil delivery line 38 leads to these chambers from the pressure lubricating system of the internal combustion engine, which, for instance, supplies the bearings of the crankshaft. In the path of delivery from line 38, ball check valves 39, 40, which are not spring loaded, are arranged ahead of the chambers 36, 37, respectively.

The chambers 36 and 37 discharge respectively through independent lines 41, 42 which have in their respective paths ball check valves 43, 44, which also are not spring loaded. The ball valves 43, 44 are arranged above the ball valves 39, 40, and there exists a direct communication between the ball valve 39 and the ball valve 43 and between the ball valve 40 and the ball valve 44. The discharge line 41 leads through bearing 3, the hollow shaft 2 and the tubular shaft 9 to a chamber 45 in shaft 9 axially ahead of the slide valve 10, whereas the discharge line 42 leads through a bearing cover 46 to a chamber 47 in shaft 2 axially in front of the slide valve 11.

During right-hand rotation of the internal combustion engine, the gear 34 of the pressure oil pump 33 is driven in the direction of arrow 48 in Figure 1. At the same time, the hollow shaft 2 is rotatably driven by the crank-shaft-driven gear 49 in one direction along with the cylinder 5, the tubular shaft 9, the piston 6, the slide valves 10, 11 and the valve-adjusting piston 12.

The piston 6, until a mean speed of rotation of perhaps 1000 r.p.m. is reached remain first of all in a position, as shown in Figure 1, in which the drive shaft 55 of an injection pump (not shown) is rotatably adjusted relative to gear 49 for a late beginning of injection by axial adjustment of the tubular shaft 9 and shaft 51, which is connected to an axial extension of shaft 9 guided inside the hollow shaft 2, to shift helical grooves 52 on shaft 51 axially relative corresponding cooperating grooves in a bearing member 53 of the gear 49. The axial splines 52 of the shaft 51 are slidable in internally-splined shaft 55.

The oil which branches off from the lubricating oil system having a pressure of, for instance, two atmospheres (2 kg./cm.²) is delivered, for right-hand rotation through the delivery line 38 past the ball valve 40 into

the chamber 37 which acts as suction chamber. From there the oil is delivered at a higher pressure by the gears 34, 35 to the chamber 36, which is effective as the dis-charge chamber, and past the ball valve 43 through the discharge line 41 to the bearing 3 and into the cham-ber 45. From the chamber 45, the oil having a pressure of approximately 10 atmospheres (10 kg./cm.²) is lead through the bore 15 in the slide valve 10 and pushes the piston 12 to the right which in turn pushes the slide valve 11 in the same direction so that it compresses the control spring 26 by means of the bolt 18 and the abut-ment 24.

When pushed to the right, as seen in Figure 1, the slide valve 11 at least partially uncovers an annular groove 57 in the tubular shaft 9 from which bores 58 through the piston 6 lead to the chamber 7 in the cylinder 5. In this way, oil, which is furnished the oil pump 33 through the supply line 38 and which has passed to discharge line 42 through the ball valve 40 as well as the ball valve 44, is delivered to the chamber 7 of the cylinder 5 by way of discharge line 42, chamber 47, bore 16 in the slide valve 11, annular groove 57 and the bore hole 58. Each of the end faces of piston 12 are pro-vided with transversely cut slots or grooves so as not to block the bores 15 or 16 when the piston abuts valves 10 or 11, respectively.

Until the engine speeds up, oil pressure in chamber 7 holds the piston 6 in the extreme right position as shown in Figure 1. With increasing engine speed, the centrif-ugally operated flyweights 30 act on abutment 23 through levers 29 and overcome the effect of the control spring 25, whereby the slide valve 10 is moved toward the left along with the abutment 23 and the bolt 17. Thus, the slide valve 10 uncovers the annular groove 59 in the tubular shaft 9 so that the oil in the chamber 45 of approximately 10 atmospheres pressure (10 kg./cm.²) flows into groove 59 and then into the chamber 8 of the cylinder 5 through bore holes 60 in piston 6. Inasmuch as the pressure in chamber 8 is larger than in the cham-ber 7, the piston 6 is moved in response to increasing engine speed to the left to a position corresponding to the deflection of the flyweights 30. When the flyweights 30 and 32 rotate at low speeds, those weights not re-strained by abutments 23 and 24 may swing outwardly as indicated for 32 in Figure 1 and for 30 in Figure 2.

In moving to the left, piston 6 and tubular shaft 9 move the shaft 51 axially so that the drive shaft 55 of the injection pump is rotatably adjusted relative to the gear 49 to advance the start of fuel injection for each cycle of engine operation. The relative angular rotation of gear 49 and shaft 55 is produced by means of helical grooves 52 on the shaft and corresponding internal heli-cal grooves in the rotatable bearing member 53 con-nected to gear 49. As indicated in the drawings, the shaft 51 is axially slidable in the injection pump drive shaft 55.

As the engine speed fluctuates, the radial position of the weights 30 will vary and accordingly adjust the axial position of valve 10, which in turn effects adjustment of the piston 6 and drive shaft 55 to adjust the fuel injection timing.

When the internal combustion engine is reversed from a right-hand rotation to left-hand rotation, as for instance by an axial movement of the camshaft to engage a new set of cams, the gear 34 in the pressure oil pump rotates in the direction opposite arrow 48. The chamber 36 be-comes the suction chamber while chamber 37 becomes the pressure chamber. Oil at approximately 10 atmospheres (10 kg./cm.²) is delivered by the pressure oil pump 33 through its pressure chamber 37, and passes the ball valve 44, through the discharge line 42, into the chamber 47 and then through bore 16 to move piston 12 to the left. Accordingly, the slide valve 10 is also moved to the left, as shown in Figure 2, uncovering groove 59.

The pressure oil which flows through the supply line

38 at a pressure the same as exists in the lubricating oil system of the internal combustion engine, for instance, 2 atmospheres (2 kg./cm.²), passes the ball valve 39 and ball valve 43 and flows through discharge line 41, chamber 45, bore 15, groove 59 and through the bore 60 in the piston 6 into the chamber 8 of the cylinder 5. The piston 6 is thereby held in a position as shown in Figure 2 in which, for left-hand rotation, the beginning of injection is retarded.

Thereafter, for controlling the timing of fuel injection for left-hand operation, the flyweights 32 act on abutment 24 to shift valve 11 axially, controlling admission of oil to chamber 7 and accordingly determining axial displacement of piston 6 and shaft 9. Inasmuch as with increasing speed, for instance above 1000 revolutions per minute, the flyweights 32 overcome the effect of the control spring 26, the slide valve 11 allows delivery of oil through groove 57 and the bores 58 in the piston 6 to the chamber 7 of the cylinder 5. The piston 6 and tubular shaft 9 are thereby moved to the right along with the shaft 51 so that a relative angular rotation of the drive shaft 55 in relation to the gear 49, corresponding to an advance or earlier beginning of injection, is produced through the helical grooves 52 and the correspondingly formed bearing member 53 of the gear 49.

The oil returning from the chambers 7, 8 of the cylinder 5 flows into the slide valves 10, 11 through the bores 58, 60, the annular grooves 13, 14 through the longitudinal grooves 19, 20, 21, 22 in the hollow shafts 9, 2 and through the bore holes 27, 28 in the abutments 23, 24 into the housing 1 and the oil sump of the internal combustion engine. If necessary, suitable means may be provided to limit the oil pressure in lines 41 and 42 to values adequate to operate the device as described without damage thereto, any excess pressure being preferably relieved to the interior of housing 1.

By the described arrangement, the reversing of an internal combustion engine from a right-hand operation to left-hand operation and vice versa may be done without any additional manipulations for setting of the timing or beginning of injection which is automatically controlled by control springs and centrifugal means in a manner dependent on the speed and direction of rotation.

In order that the two end positions of the piston 6 correctly set the beginning of injection equally before top dead center at maximum engine speeds for right-hand as well as left-hand rotation, it is advantageous to form the cams which are arranged on the drive shaft of the injection pump for the operation of the pump plungers as symmetric cams in such a manner that the beginning of delivery in one direction of rotation repeats itself in the opposite direction of rotation after rotation through an angle referred to as the symmetry angle of the beginning of delivery and, in a four-cycle engine, equal to one half of the following computation:

360°, minus angle of delivery before top dead center at maximum rotative speed, minus angle of delivery before top dead center at minimum rotative speed, minus tooth clearance of the fuel pump drive in degrees of crank.

The above-described apparatus is especially adaptable for reversible four-stroke cycle engines in which the working stroke for one direction of rotation corresponds to the compression stroke of the opposite direction of rotation.

While I have shown and described one embodiment in accordance with the present invention, it is understood that the same is not limited thereto but is susceptible of many changes and modifications within the spirit of the present invention, and I intend to cover all such changes and modifications as encompassed in the appended claims.

I claim:

1. A device for adjusting the timing of fuel injection for a reversible internal combustion engine comprising a

cylinder, a piston slidable in said cylinder, hydraulic means including pump means for applying fluid under pressure to opposite sides of said piston, a shaft member movable axially by said piston, a driven member adjusted by axial movement of said shaft member for controlling the timing of fuel injection during engine operation, valve means for controlling the application of fluid pressure to opposite sides of said piston to move the latter, and weights centrifugally actuated in response to engine speed for automatically operating said valve means to correspondingly adjust the fuel injection timing for rotation of said engine at different speeds in either direction, said shaft being axially movable in one direction to advance the fuel injection for one direction of engine rotation and being axially movable in the opposite direction to advance the fuel injection for rotation of the engine in the opposite direction.

2. A device according to claim 1, wherein the cylinder, piston, valve means, shaft and weights are rotated at a speed dependent on engine speed and further including helically grooved members for coupling said shaft to an engine crankshaft, said grooved members being relatively rotatably adjusted by axial displacement of said shaft.

3. A device for adjusting the timing of fuel injection for a reversible internal combustion engine comprising a cylinder, a piston slidable in said cylinder, hydraulic means including pump means for applying fluid under pressure to opposite sides of said piston, a shaft member movable axially by said piston, a driven member adjusted

30 by axial movement of said shaft member for controlling the timing of fuel injection during engine operation, valve means for controlling the application of fluid pressure to opposite sides of said piston to move the latter, and weights centrifugally actuated in response to engine speed for automatically operating said valve means to correspondingly adjust the fuel injection timing for rotation of said engine at different speeds in either direction, said shaft being axially movable in one direction to advance the fuel injection for one direction of engine rotation

35 and being axially movable in the opposite direction to advance the fuel injection for rotation of the engine in the opposite direction, said cylinder, piston, valve means, shaft and weights being rotated at a speed dependent on engine speed and further including helically grooved members for coupling said shaft to an engine crankshaft, said grooved members being relatively rotatably adjusted by axial displacement of said shaft, said valve means comprising a separate valve for controlling displacement of the piston for each direction of engine rotation, each

40 of said valves having a separate centrifugally actuated valve operating weight, said pump means comprising a reversible pump having its direction of rotation dependent on the direction of engine rotation, and means responsive to the direction of rotation of said pump for rendering one or the other of said valves, respectively, inoperable by its associated weight.

4. A device for adjusting the timing of fuel injection for a reversible internal combustion engine comprising a cylinder, a piston slidable in said cylinder, hydraulic means including pump means for applying fluid under pressure to opposite sides of said piston, a shaft member movable axially by said piston, a driven member adjusted by axial movement of said shaft member for controlling the timing of fuel injection during engine operation, valve

45 means for controlling the application of fluid pressure to opposite sides of said piston to move the latter, and weights centrifugally actuated in response to engine speed for automatically operating said valve means to correspondingly adjust the fuel injection timing for rotation of said engine at different speeds in either direction, said

50 shaft being axially movable in one direction to advance the fuel injection for one direction of engine rotation and being axially movable in the opposite direction to advance the fuel injection for rotation of the engine in the opposite direction, said cylinder, piston, valve means,

<p

shaft and weights being rotated at a speed dependent on engine speed and further including helically grooved members for coupling said shaft to an engine crankshaft, said grooved members being relatively rotatably adjusted by axial displacement of said shaft, said valve means comprising a separate valve for controlling displacement of the piston in response to the engine speed for each direction of engine rotation, said pump means including a reversible pump, the pumping direction of which is dependent on direction of engine rotation, and means responsive to the direction of pumping of the pump for rendering one or the other of said valves, respectively, inactive with regard to control of piston position for different engine speeds.

5. A device according to claim 4, wherein said last-mentioned means includes a second piston engageable with both said valves and movable in response to fluid pressure from said pump.

6. A device according to claim 5, wherein said valves and the second piston are slideable in a tubular structure fixed to the first-mentioned piston.

7. A device according to claim 4, wherein said valves are coaxially and slidably arranged and wherein the pump delivers oil at one pressure to actuate the piston in one direction, the oil delivery being controlled by one of the valves while the other valve simultaneously admits oil at lower pressure to the opposite side of the piston when the engine is rotating in one direction and wherein for rotation of the engine in the opposite direction the relationship of oil pressures and the controlling action of the valves is reversed.

8. A device according to claim 4, wherein oil conduits are connected between said pump and said valves and wherein for one direction of engine rotation one conduit carries oil to one valve at one pressure and another con-

30
35
20
25
30
35

duit carries oil to the other valve at lower pressure and wherein for the opposite direction of engine rotation the relationship of oil pressures in said conduits is reversed.

9. A device according to claim 8, wherein the oil pump which furnishes oil for adjusting the piston is connected to a lubricating oil system of the internal combustion engine which is also under pressure.

10. A device according to claim 8, wherein the oil pump comprises two chambers which may be alternately interchanged as suction and pressure chambers depending from the direction of rotation of the engine, each chamber being provided with inlet and outlet check valves.

11. A device according to claim 10, wherein said check valves are ball valves, unbiased except by gravity and oil pressure.

12. A device according to claim 10, wherein the inlet valves for each of the pump chambers are connected in common to an engine lubricating system supply while the other valves of each pump chamber are connected to independent discharge lines, one of said lines carrying oil at the pressure of the engine lubricating system and the other line carrying oil from the pump at a higher pressure when the engine rotates in one direction, the pressure relationships in said lines being reversed for engine rotation in the opposite direction.

13. A device according to claim 12, wherein said independent discharge lines are connected to deliver oil axially at opposite sides of said piston.
